ATTORNEY

UNITED STATES PATENT OFFICE.

JOHN W. MEYERS, OF ELYRIA, OHIO.

REVERSIBLE INTERCHANGEABLE RUBBER HEEL.

1,417,275.

Specification of Letters Patent. Patented May 23, 1922.

Application filed July 17, 1920. Serial No. 327,130.

To all whom it may concern:

Be it known that I, JOHN W. MEYERS, a citizen of the United States, residing at Elyria, in the county of Lorain and State of Ohio, have invented a certain new and useful Improvement in Reversible Interchangeable Rubber Heels, of which the following is a full, clear, and exact description, reference being had to the accompanying drawings.

An object of my invention is the provision of a rubber heel having means other than nails, whereby it may be easily and quickly applied to a shoe and be securely held during use. Another object is to provide adjustable detachable heel securing means, which will permit a pair of rubber heels after being partially worn to be readily reversed on the shoes, that is, the heels to be detached from the shoes and the left heel applied to the right shoe, and vice versa, thus increasing the wear available from a pair of heels nearly 50%. The same means, of course, will also permit a pair of rubber heels when worn out to be readily replaced by a new pair without involving the expense and delay ordinarily incurred in having worn heels replaced.

More specifically it is my object to provide complementary attaching members, one of which may be secured to the bottom of the heel portion of the shoe, and the other of which may be formed in the commercial rubber heel, during the process of manufacture in such manner that rubber heels containing one of the members may be readily engaged or disengaged from the shoe carrying the other member for reversal or replacement, when desired, and yet be securely retained on the shoe during use.

An important feature of my invention is the elimination of nails from the heel. With the fastening means as provided, the wearing surface or tread is entirely free from nails or other metallic attaching means, and the upper surface of the sole above the heel is not studded with the ends of nails which frequently project through and perforate the heel portion of the hosiery and cause considerable discomfort to the wearer. Another important feature that aids in providing a secure attaching means for the heel, is the formation of one of the attaching members of connected resilient metal loops or eyes, which are embedded in the rubber during the manufacture of the heel, and which permits the combined resilient effects

of the metal and the rubber to function in attaching and securing the heel to the shoe.

Other features and objects are hereinafter more fully described and the essential characteristics of the invention are summarized in the claims.

My invention is illustrated in the drawings wherein Fig. 1 is a view showing the tread side of a heel embodying features of my invention; Fig. 2 is a plan of a heel embodying features of my invention and represents the opposite face of the heel shown in Fig. 1; Fig. 3 is a vertical section through a heel showing the fastening means between the heel and shoe.

My invention contemplates, in general, the construction of a heel which may be conveniently secured to a shoe without the employment of nails. Conversely, my invention provides for a construction that enables a heel to be readily removed from a shoe, for purposes of replacement or for purposes of transposing from one shoe to another. In carrying out my invention I prefer to employ a fastening means, which is similar in operation to the ordinary glove fastener, in that, it is capable of being readily attached or disengaged by the wearer.

Referring now to the drawings, and designating the parts shown therein by the use of reference characters, 10 represents any form of rubber heel, which is suitable for being used with my invention. The heel which I have shown is provided with a tread 11, and a crown 12 on the wearing surface thereof. On the opposite surface this heel is shown as provided with an annular groove 13, which is spaced inwardly from the marginal edges of the heel, and cut slightly into the body portion thereof, for receiving a plate, which will be hereinafter described. In Fig. 3 that portion of the heel extending from the outer periphery of the groove 13 to the marginal edge 25 may be tapered, as at 14, to enable the marginal edges to be spread outwardly, when the heel is pressed against the shoe. This outwardly spreading action serves to form an effective contact or seal between the heel and shoe.

In carrying out the snap fastener principle for securing the heel to the shoe, I prefer to employ an endless member 15 preferably constructed of wire, which may be imbedded in the rubber when the heel is molded, and which may be shaped in such manner as to form flexible loops at various points therein. In Fig. 2 such an endless wire is

represented as having post engaging loops, as at 16, and expansion or connecting loops as at 17. The number of post engaging loops is of course optional and varies with 5 the size of the heel to be used. For certain purposes the shape and size of the rubber heel does not permit the employment of a wire loop, and in such cases I may employ a single socket, similar to a glove fastener 10 socket, in place of the wire loop.

To secure the heel to the shoe, I provide a plate 18 which may be removably secured and adjusted to the shoe independently of the heel. Such a plate is shown in Fig. 3 15 as being corrugated as at 24 around the marginal edges thereof. The shape of the corrugation is such as to be substantially complementary with the groove 13 in the heel, into which it is adapted to extend. To secure the plate to a shoe I prefer to employ 20 a set of screws 19, which extend through elongated apertures 20. The shape of these apertures permits the adjustment of the plates without removing the screws from the 25 shoe, and therefore enables the interchangeability of the heels without necessitating the cutting away of portions thereof to form a neat joint with the lift of the shoe. In Fig. 30 2 it will be noted that the marginal edge of the plate, as at 21, extends beyond the bearing surface of the plate. The purpose for this offset marginal edge is to cause the plate to clinch the shoe when the screws 19 are drawn tightly into the shoe.

35 The posts, which are adapted to be carried by the shoe and to engage with the aforementioned loops in the heel, are represented at 22, as being rigid with the plate 18 and spaced around the corrugated portion thereof. These posts may be similar to the posts 40 employed in the ordinary glove fastener and correspond in number with the fastener loops 16 in the rubber heel. By spacing the posts around the corrugated portion of the 45 plate rather than on the bearing surface thereof, it is not necessary for the cobbler to pierce the leather of the shoe to provide a bearing surface for one end of the post. Furthermore, in the process of molding the 50 heel, the plate may be employed as a templet to center the loops with relation to the post, prior to the vulcanization of the rubber.

To attach the heel to the shoe, the plate 55 18 is secured to the lift and adjusted thereon by means of the screws 19 in such a manner that the posts 22 extend downwardly from the shoe. The heel 10 is then brought 60 into engagement with the plate, by bringing the groove 13 into registration with the corrugated portion 24 on the plate, and is then forced toward the shoe until the loops in the member 15 are snapped over the individual posts, whereupon the shoe is ready for use. To reverse the heels from one shoe to another, it is only necessary to disengage the 65

arms from the respective shoes and to transpose them, according to the manner above set forth. If the heels do not align with the lifts in their transposed position, then it is only necessary to loosen the screws 19 and to 70 shift the plate 18 until the proper adjustment is attained.

From the foregoing description it will be seen, that I have provided a means for securing a heel to a shoe which enables such 75 heel to be attached by means of a simple operation, without employing nails or other fastening means of a permanent character. An advantage of my invention is that heels after being partially worn may be transposed from one shoe to another, whereby the 80 life of one pair of heels is materially increased.

Having thus described my invention, I 85 claim:

1. Means for attaching a rubber heel to a shoe comprising a metal plate, of similar shape, but smaller than the heel, adjustably secured to the heel portion of the shoe, said plate having a shouldered flanged periphery 90 extending both above and below the plane of the central portion, and spaced headed studs secured to said plate adjacent the periphery adapted to cooperate detachably with socket members formed in a rubber 95 heel.

2. A rubber heel and means therein for attaching the same to a shoe, comprising a lift having a groove, spaced from the periphery, in its face opposite the tread, the 100 surface of said face within said groove being slightly below its surface of the periphery, and the portion of said face between said groove and the periphery being substantially uniformly inclined, spaced cavities 105 in said groove, and connected resilient metallic eyes embedded in said heel and registering with said cavities.

3. In combination, a rubber heel, a plate having a similar shape, but smaller size than 110 the heel, said plate having a corrugation extending around the periphery thereof, the outer edge of the corrugation being carried beyond the plane of the central portion, whereby the marginal edges of the plate 115 grip the shoe when secured thereto, a spaced pair of studs carried by the plate adjacent the corrugated portion thereof, said heel having a shallow recess complementary to the corrugated portion of the plate and having sockets complementary to said studs and in registration therewith, the shoe engaging portion of the heel being tapered inwardly from the marginal edges to said recess, and an endless wire loop imbedded in the heel 120 and adapted to embrace the studs for holding the heel to the plate.

In testimony whereof, I hereunto affix my signature.

JOHN W. MEYERS.
